UNITED STATES PATENT OFFICE.

SIMON SIMONEAU, OF SPRINGFIELD, MASSACHUSETTS.

BRICK-ELEVATOR.

1,177,544.

Specification of Letters Patent. Patented Mar. 28, 1916.

Application filed May 25, 1915. Serial No. 30,372.

To all whom it may concern:

Be it known that I, SIMON SIMONEAU, a subject of the King of Great Britain, residing at Springfield, in the county of Hampden and State of Massachusetts, have invented new and useful Improvements in Brick-Elevators, of which the following is a specification.

The invention relates to elevators, and 10 more particularly to the class of automatic brick elevating machines.

The primary object of the invention is the provision of a machine of this character wherein the necessity of handling the bricks 15 by the tossing of the same from the ground to an elevated point for the stacking thereof is entirely obviated, as the said bricks are placed upon carriers which are automatically lifted to the point of elevation, whence 20 the said bricks are removed from the respective carriers and finally placed upon the kiln or brick rack, thus assuring the handling of the bricks with despatch.

Another object of the invention is the provision of an elevator of this character wherein the carriers are mounted for travel in a 25 novel manner, the endless conveyer being also novel in form to prevent slipping thereof when being driven from a motor.

30 A further object of the invention is the provision of an elevator of this character which can be transported from one point to another for the convenience in the stacking of bricks or elevating the same to a kiln.

35 A still further object of the invention is the provision of a machine of this character which is simple in construction, reliable and efficient in its operation, strong, durable, and inexpensive in manufacture.

40 With these and other objects in view, the invention consists in the construction, combination and arrangement of parts as will be hereinafter fully described, illustrated in the accompanying drawings, and pointed out in 45 the claim hereunto appended.

In the drawings:—Figure 1 is a side elevation of a machine constructed in accordance with the invention. Fig. 2 is a front elevation thereof. Fig. 3 is a vertical longitudinal sectional view through the machine. Fig. 4 is a vertical transverse sectional view. Fig. 5 is a sectional view on the line 5—5 of Fig. 1. Fig. 6 is a horizontal transverse sectional view through the boom, showing 55 the manner of connecting the fork of the

bracket therewith. Fig. 7 is a sectional view through one of the chain wheels.

Similar reference characters indicate corresponding parts throughout the several views in the drawings.

60

Referring to the drawings in detail, the machine comprises a body 10 supported upon axles 11 carrying traction wheels 12 of any approved form, and within the body is located a motor 13, which is preferably of the gasoline type, and has connection with a shaft 14, which, through the medium of a train of gearing 15, is connected with an endless elevator hereinafter fully described.

65 Fixed to and rising from the top of the body 10 is a crane comprising a bracket 16 which is formed with a fork 17 having grooves 18 on which is detachably engaged the reduced rounded end 19 of a boom or arm

20 on the upper end of which is fixed a detachable head 21, and in the sides of the body 10 and the said head 21 are journaled the respective shafts 22 and 23 on which are

fixed chain wheels 24, each being formed with a peripheral groove 25 and transverse notches 26 at intervals in its periphery, and in these grooves 25 are received the endless chains having at intervals transverse pins

which engage in the notches 26 to prevent the slipping of the chains on the said wheels 80 24. The chains 27, together with the transverse hanger rods 29, which are fixed therein, constitute the elevator, and upon the hanger rods are suspended carriers comprising

platforms 30 in which are fixed the hangers 31 loosely connected to the rods 29, and upon these platforms are adapted to be placed a plurality of bricks to be elevated.

85 90 95 90 A still further object of the invention is the provision of a machine of this character which is simple in construction, reliable and efficient in its operation, strong, durable, and inexpensive in manufacture.

100 105 100 With these and other objects in view, the invention consists in the construction, combination and arrangement of parts as will be hereinafter fully described, illustrated in the accompanying drawings, and pointed out in the claim hereunto appended.

It is of course understood that the shaft 22 is in gear with the train of gearing 15 driven by the shaft 14, which is in turn actuated by the motor. The machine can be transported from one point to another, and when located at the proper point, bricks can be placed upon the carriers for elevating the same from the ground to a point overhead on to a brick rack or kiln.

110 From the foregoing description, taken in

connection with the accompanying drawings, the construction and manner of operation of the device will be clearly understood, and therefore a more extended explanation 5 has been omitted.

What is claimed is:—

A machine of the class described comprising a body, a vertical boom carried by the body and having a forked bracket fixed to 10 its upper end and extending at right angles therefrom, the said body being cut away at one end, bearings mounted in the cut away portion, shafts journaled in the bracket and in the said bearings, peripherally grooved 15 wheels fixed to said axle shafts and having

notches opening into the grooves and through the peripheries thereof, endless sprocket chains trained over the said wheels and traveling in the grooves in the peripheries thereof, transverse bars pivoted in the 20 chains and received in the notches in said wheels, and carriers, each including a platform and hangers pivotally connected to the transverse bar.

In testimony whereof I affix my signature 25 in presence of two witnesses.

SIMON SIMONEAU.
